UNITED STATES PATENT OFFICE.

ALFRED N. GOLDSMITH, OF MOUNT VERNON, NEW YORK, ASSIGNOR TO RADIO CORPORATION OF AMERICA, A CORPORATION OF DELAWARE.

SOUND-REPRODUCING MACHINE.

Application filed September 9, 1922. Serial No. 587,068.

This invention relates to sound reproducing machines and particularly to a horn adapted for use with a plurality of sets of sound reproducing apparatus designed to be operated 5 selectively as desired by the user.

In the use of machines comprising more than one set of sound reproducing apparatus, for example, radio receiving apparatus and phonographic apparatus, it is very desirable 10 for considerations including attractiveness of appearance and economy of manufacture that the sound reproducing machine shall be provided with but one horn to which sound is communicated both from the radio receiving 15 apparatus and the phonographic apparatus. In sound reproducing machines of the above-mentioned type and having a single horn, difficulty has, however, been experienced in obtaining good acoustic results from the horn 20 with either of the sets of sound reproducing apparatus. This difficulty is believed to have been due to a tendency on the part of the sound communicated to the horn from one of said sets of apparatus to divide in the horn 25 and to enter the conduit which connects the horn to the other set of sound reproducing apparatus.

It is an object of this invention to provide a horn for use with a plurality of sets of 30 sound reproducing apparatus, which will give uniformly good results whether sound is communicated to it from one or another of the sets of sound reproducing apparatus.

To this end an important feature of the 35 invention resides in the provision of a horn having a single mouth or discharge opening and two inlet conduits and also having a baffle plate mounted between the inlet conduits and arranged to cause sound waves, 40 communicated to either of said conduits, to be directed toward the discharge opening before leaving the conduit. Preferably, the horn is also so formed as to cause the inlet conduits to extend in substantial parallelism with each 45 other throughout the major portion of its length.

In accordance with a further feature of the invention, the horn is provided with a discharge opening and two inlet openings, one 50 of the inlet openings being provided in a part extending laterally from the body portion of the horn and the other inlet opening being in communication with a tubular member; said part and the body portion of the 55 horn being formed to provide a conduit taper-

ing from the free end of the part to the discharge opening, and the tubular member and the body portion being formed to provide a second conduit analogous to the first-mentioned conduit and tapering from the outer 60 end of the member to the discharge opening. With this construction, if one set of sound reproducing apparatus is connected with the outer end of one of said conduits, and another set of sound reproducing apparatus is connected with the outer end of the other conduit, 65 excellent acoustic effects may be obtained from the horn whether sound is communicated to it from one or the other of said sets of apparatus. In the illustrated embodiment of the invention, radio receiving apparatus is connected with the free end of the laterally extending part and phonographic apparatus is connected with the outer end of 70 the tubular member. 75

Still further objects and features of the invention will appear as the description proceeds and will be pointed out in the appended claims.

In the drawing in which like reference 80 numerals designate like parts in the various views,

Fig. 1 is a front view of the upper part of a machine embodying the invention, with the cover of the machine in open position and 85 with a portion of the machine casing broken away so as better to reveal the phonographic apparatus.

Fig. 2 is a view in perspective with the plate in the upper part of the main portion 90 of the machine casing removed and with the top wall of the casing partly broken away to reveal the horn.

Fig. 3 is a view of the horn in longitudinal section, and, 95

Fig. 4 is a perspective view of the horn looking generally from the front of the machine.

In the illustrated construction, the main portion 2 of the casing of the machine is provided in its upper end with a compartment 4 in which is located a flared structure 6, the rear end of which is in communication with the mouth or discharge opening 8 of a horn 10. As shown, the horn 10 is formed to provide front and rear inlet conduits 12 and 14 respectively and is provided with a part 16 formed integrally therewith and extending laterally and forwardly within the compartment 4. The part 16 communicates with the 100 105 110

front conduit 12 of the horn and has a passage 18 constituting an inlet opening for the conduit 12.

Secured to the outer or free end of the laterally extending part 16 of the horn 10 is a telephone 20 which is connected with radio receiving apparatus mounted in the cover portion 22 of the machine casing. A convenient means for supporting the radio receiving apparatus within the cover 22 of the machine comprises a panel 24 spaced from the top wall of the cover to provide a chamber within which the radio receiving apparatus may be contained. The radio receiving apparatus is mounted on the inner side of the panel 24, and the panel is formed with an opening 26 in which the vacuum tubes 28 of the radio receiving apparatus are disposed, thus enabling ready access to be obtained to the tubes for inspection and replacement. In order to enable the radio receiving apparatus to be readily operated, it is provided with suitable controlling elements extended through the panel 24 for manipulation from outside of the chamber in which the radio receiving apparatus is housed. These controlling elements may include a main switch 30 by which the operation of the radio receiving apparatus may be initiated or suspended, a knob 32 by which the inductance of the primary and secondary circuits may be regulated in accordance with the wave length which it is desired to receive, devices 34 for adjusting the condenser in the secondary circuit according to the wave length to be received, devices 36 for similarly adjusting or tuning the primary circuit of the radio receiving apparatus and a knob 38 by which the primary and secondary circuits may be more loosely or more closely coupled to obtain softer or louder response from the machine. The radio receiving apparatus constitutes per se no part of the present invention and is fully disclosed in my co-pending application Serial No. 587,067, filed Sept. 9, 1922, for sound reproducing machine. Accordingly, further disclosure of the radio receiving apparatus in this application is deemed unnecessary.

The upper and smaller end of the horn 10 is seated in the top wall 40 of the main portion 2 of the machine casing, and is provided with an inlet opening 42 which communicates with the rear inlet conduit 14 of the horn. Connected with the upper end of the horn 10 above the wall 40 is a tubular arm 44 mounted to swing horizontally relatively to the horn and carrying at its outer end a sound box 46 which is provided with a needle 48 adapted to ride on a phonograph record supported on a turn table 50.

It will be apparent from the foregoing that the front and rear inlet conduits 12 and 14 of the horn 10 are connected respectively with radio receiving apparatus mounted in the cover 22 of the machine casing and with

phonographic apparatus, and that the radio receiving apparatus and phonographic apparatus may be operated selectively as desired by the user of the machine. Moreover, it will further be understood that when the radio receiving apparatus is being operated, sound is communicated by the telephone 20 to the part 16 and conduit 12 and issues from the mouth 8 of the horn and, that on the other hand, when the phonographic apparatus is being operated, sound is transmitted through the tubular arm 44 to the rear inlet conduit 14 and thence to the mouth of the horn.

In order to prevent sound communicated to the horn 10 through the inlet conduit 12 or 14 from dividing in the space within the horn and passing back into the other conduit, the horn is provided with a baffle 52 interposed between the inlet 42 of the rear conduit 14 and the channel 18 of the laterally extending part 16 and so constructed as to cause sound communicated to the horn through either the inlet opening 42 or the laterally extending part 16 to be directed toward the discharge opening 8 before leaving the conduit 14 or 12 respectively. Preferably and as shown, the baffle 52 is not only so arranged as to direct the sound waves toward the discharge opening 8 within the conduits 12 and 14, but, in order to provide complete assurance against any backing up of sound waves communicated to the horn through one of the conduits into the other conduit, is extended to a point adjacent to the mouth of the horn, so as to cause the conduits to extend in substantial parallelism throughout the major portion of the length of the horn.

It will be further noted that in the illustrated construction, the laterally extending part 16 and the body portion of the horn 10 are formed to provide an inlet conduit tapering without any sharp angles or abrupt changes in the transverse area of the conduit from the outer or free end of the part 16 to the mouth 8 of the horn, and that the tubular arm 44 and the rear conduit 14 also provide an inlet conduit tapering gradually from the outer end of the arm 44 where it is connected with the sound box 46 to the mouth of the horn. Moreover, it will be seen that the inlet conduits provided respectively by the part 16 and the body portion of the horn and by the tubular arm 44 and the body portion of the horn resemble each other closely with respect to size and degree of taper, so that the acoustic effect of the horn on sound communicated to it from one of the sets of sound reproducing apparatus is similar to its effect on the sound communicated to it from the other set of sound reproducing apparatus.

Although the horn has been described in its application to sound reproducing machines comprising radio receiving apparatus and phonographic apparatus, it is recognized that it may be employed with sets of sound re-

producing apparatus of any desired type and whether of like or different character.

Having described my invention, what I claim is:

5. In a sound reproducing machine, a horn comprising a body portion having a discharge opening at one end and an inlet opening at the other, and also comprising a part extending laterally from the body portion, said part and said body portion being formed to provide a conduit tapering from the free end of said part to the discharge opening of said body portion and said body portion being formed with a second conduit communicating with said discharge opening and tapering from said inlet opening to said discharge opening.
10. 2. In a sound reproducing machine, a horn comprising a body portion having a discharge opening at one end and an inlet opening at the other, and also comprising a part formed integrally with said body portion and extending laterally from the body portion, said part and said body portion being formed to provide a conduit tapering from the free end of said part to said discharge opening, and said body portion being formed to provide a second conduit tapering from said inlet opening to said discharge opening and arranged in substantial parallelism with the first-mentioned conduit throughout the major portion of the length of the horn.
15. 3. In a sound reproducing machine, a horn comprising a body portion having a discharge opening in its front face at one end and an inlet opening at the other end, and also comprising a part extending laterally from the body portion, said body portion being formed to provide conduits tapering from the inlet end of the horn to the discharge opening, said conduits being arranged one in front of the other and with the rear conduit in communication with said inlet opening and said part being formed with an inlet opening communicating with the front conduit.
20. 4. In a sound reproducing machine, a horn comprising a body portion having a discharge opening at one end and an inlet opening at the other, and also comprising a part extending laterally from the body portion, said part and said body portion being formed to provide a conduit tapering from the free end of said part to said discharge opening, and a separate tubular member connected to the inlet opening of the body portion of the horn, said tubular member and said body portion being formed to provide a conduit analogous to the first-mentioned conduit and tapering from the outer end of said member to said discharge opening.

5. In a sound reproducing machine, a horn having a single discharge opening and two inlet conduits, a baffle mounted in the horn between the inlet conduits, and two independent sets of sound reproducing apparatus connected respectively with said conduits.

6. In a sound reproducing machine, a horn having a single discharge opening at one end and an inlet opening at the other and comprising a body portion formed to provide two conduits arranged one in front of the other, said conduits communicating with said discharge opening and the rear conduit communicating also with said inlet opening, and said body portion also comprising a part extending laterally therefrom and provided with an inlet opening for the front conduit, phonographic apparatus connected with the first-mentioned inlet opening and radio receiving apparatus connected with said part.

7. In a sound reproducing machine, a horn comprising a body portion, said body portion having a discharge opening in its front face at one end, an inlet opening at the other end, and a rear conduit extending from said discharge opening to said inlet opening, said horn also comprising an extending side portion with an inlet opening in its free end, said horn having a front conduit extending from said discharge opening to the inlet opening in said side portion.

8. In a sound reproducing machine, a horn comprising a body portion, said body portion having a discharge opening in its front face at one end and an inlet opening at the other end and a rear conduit extending from said discharge opening to said inlet opening, said horn also comprising an extending side portion with an inlet opening in its free end, said horn having a front conduit extending from said discharge opening to the inlet opening in said side portion, and a separate tubular member connected to the inlet opening of said body portion to coact with said rear conduit to form a conduit similar to said front conduit.

9. In a sound reproducing machine, a horn comprising a body portion having a discharge opening in its front face at one end and an inlet opening in the other end, and also comprising a part extending laterally from the body portion, said body portion being formed to provide conduits extending from the inlet end of the horn to the discharge opening and being arranged one in front of the other and with one of said conduits in communication with the said inlet opening, and said part being formed from an inlet opening communicating with the other conduit.
